[57] CLAIM

The ornamental design for a necktie, as shown and described.

DESCRIPTION

FIG. 1 is a perspective view of the necktie showing our new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a bottom plan view thereof; and

FIG. 7 is a right side elevational view thereof.

The cross hatch pattern shown in FIGS. 1-3 is understood to repeat throughout the indicated area.

FIG. 4

FIG. 5

FIG. 6

FIG. 7
